LEWIS ASPER, OF MINNEAPOLIS, MINNESOTA

STORM SASH HOLDER

Application filed April 12, 1930. Serial No. 443,712.

This invention relates to storm sash holders and has for an object to provide a simple, inexpensive and highly efficient device associated with a window frame for securing the storm sash or analogous article in a variety of desired open positions and also in closed position.

It is a further object to provide a neat, compact storm sash holder, which will not rattle and which will prevent the sash from rattling or becoming displaced when open or partially open and which will not interfere in any way with the operation of the upper and lower sashes of the window.

Another object is to provide a sash holder of the type above described, which includes highly efficient frictional means associated with a pair of pivoted links, whereby the storm sash may be adjusted to a desired open position by merely swinging the lower edge thereof outwardly or inwardly as the case may be, the frictional elements securely holding the sash against rattling and displacement.

Still another object is to provide a compact sash holder which may be easily and conveniently attached to conventional storm sash and window frames now extensively used and which is provided with a highly efficient attachment bracket secured upon the window frame and enabling the storm sash and holder to be instantly disconnected when it is desired to remove and store the storm sash, the disconnected portions of my sash holder being connected to the storm sash and folded in compact position to facilitate a number of the storm sashes being piled or stacked.

These and other objects and advantages of the invention will be fully set forth in the following description made in connection with the accompanying drawings wherein like reference characters refer to similar parts throughout the several views and wherein,

Fig. 1 is a vertical section taken through a conventional type of window frame having a storm sash mounted therein and provided with a preferred embodiment of my invention;

Fig. 2 is a cross section taken on the line 2-2 of Fig. 1;

Fig. 3 is a fragmentary view on a larger scale showing one of the storm sash holders extended to full open position;

Fig. 4 is a side elevation of the same;

Fig. 5 is a vertical section taken on the line 5-5 of Fig. 4, showing the structure of the attachment bracket for the window frame;

Fig. 6 is a detail perspective view showing a friction means at the pivot joint of the links of the sash holder;

Fig. 7 is a cross section taken on the line 7-7 of Fig. 4; and

Fig. 8 is a fragmentary section showing lapped portions of the two links when the links are folded together in closed position and showing means for retaining the links against displacement.

In the drawings, a conventional type of window frame is shown having a sill S, the usual blind stop B and other elements common in most types of window frames. The storm sash X is of a conventional type and is swingably connected at its upper edge by straps or eyes Y to hooks Z secured to the upper jamb of the window frame. The lower member or rail of the storm sash X is provided with a suitable handle H by which the storm sash may be swung to open or closed position. My sash holders each comprise a pair of pivoted links associated with the storm sash and the window frame (usually the blind stop of the window frame) for adjustably holding the storm sash in a desired open position and for permitting the sash to be entirely closed flush against the blind stop. Ordinarily two of these devices are used for each installation and since the devices are identical, for the purpose of brevity, only one thereof will be described.

The said device comprises a pair of flat links 10 and 11 respectively, pivoted together by suitable means, such as a rivet 12, adjacent their inner ends. The outer link 10 projects at its inner extremity some distance beyond the pivot 12 and carries a resilient clip 13 bowed slightly and clamped under tension by the rivet 12 which extends

- through the approximate center thereof. Clip 13 may be constructed of suitable resilient material and is provided at each of its ends and along its longitudinal edges with 5 inturned projections forming two pairs of straddling members for engaging the longitudinal edges of link 10 adjacent the pivot to prevent oscillation of the clip upon the link. Three of said inturned projections 10 are numbered 13a and terminate inwardly of or at least flush with the inner surface of link 10. The upper projection numbered 13b adjacent the extremity of link 10 is projected beyond the longitudinal edge of link 15 10 in order to engage and abut the longitudinal edge of link 11 when the links are swung outwardly into longitudinal alinement. This positively holds the links extended in a straight line with the storm sash 20 opened to its full limits with my device applied. The link 10 at its outer end is pivoted by suitable means, such as a rivet 14, with the out-turned ear of a small angle bracket 15 having an attachment base which is secured by suitable means, to a point at one 25 side and adjacent the lower rail of the storm sash X. The link 11 is detachably pivoted to a small and compact bracket 16 which is secured to the window frame and preferably 30 to the side of the blind stop B. Bracket 16 comprises a vertically disposed plate having adjacent the upper portion thereof a short projecting stud or pin 16a which is adapted to receive the end of link 11 passing through 35 an aperture 11a formed in said end, and a retaining lever 17 is pivoted by a rivet 18 to bracket 16 at a point below pin 16a, said lever having a relatively short and slightly offset end 17a which is adapted to engage 40 and slide over the outer end of pin 16a and the outer surface of the connected end of the link 11, preventing displacement of the link from the bracket while permitting pivotal movement of the link 11 upon the pivot pin. 45 The handle end 17b is elongated to permit the lever to be easily manipulated for attaching or detaching my storm sash holder from the window frame.
- When the storm sash is fully closed against 50 the blind stop B, the links 10 and 11 will be swung together and superimposed in the position shown by the dotted lines in Fig. 1, and to assist in holding the links in superimposed position, and thereby prevent accidental opening of the storm sash, I may provide a small projection 11b on one of the 55 links adapted to register and interlock with a detent 10a formed in the appropriate surface of the other link, when the links are swung together in fully closed position. The links 10 and 11 are preferably formed of metal or material having some resiliency and the links may be swung apart by applying slight force.
- 60 65 The clip 13 in addition to limiting the out-

ward swinging movement of the links and holding the links in longitudinal alinement also yieldingly forces the pivoted ends of the links into frictional engagement, since the resilient clip is under considerable tension supplied by the rivet 12. The flat opposed surfaces of links 10 and 11 adjacent the common pivot afford considerable frictional area and the structure with the clip is so efficient that the storm sash may be held frictionally in any open position between closed position and the fully open position illustrated in the drawings, without the addition of other clamping or locking means.

To open or close the storm sash, assuming the links 10 and 11 to be out of longitudinal alinement, it is only necessary to grasp the handle H and swing the storm sash to the desired position. When, of course, the storm sash is in full open position, with the links longitudinally alined, it is necessary to first tap the connected ends of the links upwardly and then the sash may be swung inwardly.

In connecting or disconnecting the inner link 11 with the bracket 16, retaining lever 17 is swung slightly out of vertical position whereupon the apertured end of link 11 may be engaged with or disengaged from the pivot stud 16a. It will be seen that with this readily detachable connection, the storm window may be readily installed upon or detached from the window frames.

When the storm windows are detached, the links 10 and 11 are folded upon each other and swung compactly against the frame of the sash whereafter the storm windows may be stacked or piled conveniently.

It will be seen that with my device, no part of the links or other elements ever project inwardly in the path of the upper and lower sashes of the window.

From the foregoing description, it will be seen that I have invented an extremely simple and improved storm sash holder, which may be manufactured at very low cost, which will be effective to hold a storm sash in a variety of different open positions and by which the storm sash may be adjusted without releasing hooks, clamping devices or other means. The frictional connection between the links, connections of the links with the attachment brackets, as well as the fact that the links are relatively short prevent the devices and the storm window from rattling or working loose.

It will, of course, be understood that various changes may be made in the form, details, arrangement and proportions of the parts without departing from the scope of my invention, which, generally stated, consists in a device capable of carrying out the objects above set forth, in the novel parts and combinations of parts disclosed and defined in the appended claims.

What is claimed is:

1. In a storm sash holder, a pair of links connected with a storm sash and a window frame respectively, said links having lapped inner ends, a pivot member connecting the lapped ends of said links and a tensioned resilient member carried by one of said links and interposed between one end of said pivot member and said link to force the lapped surfaces of said links together, and said resilient member having means for engaging said carrying link to prevent relative oscillation between said link and resilient member.
- 15 2. In a storm sash holder, a pair of pivoted links connected at their outer ends with a storm sash and a window frame respectively, the inner ends of said links being lapped, a pivot member connecting the said lapped ends, a tension spring clip interposed between one end of said pivot member and one of said links to force the lapped surfaces of said links together, and means for preventing oscillation of said clip with reference to said last mentioned link and said clip having a lateral and angular projection for engaging one of the edges of the other link when the links are swung to a predetermined position.
- 30 3. In a storm sash holder, a pair of pivoted links connected at their outer ends with a storm sash and a window frame respectively, the inner ends of said links overlapping, a pivot member connecting said lapped ends and a bowed resilient clip interposed between one end of said pivot member and one of said links to force the lapped surfaces of said links together, said clip having means for straddling the longitudinal edges of one of said links.
- 35 4. In a storm sash holder, a pair of links connected with a storm sash and a window frame respectively, said links having lapped friction surfaces at their inner ends, a pivot member connecting the lapped ends of said links, a bowed resilient member interposed between one end of said pivot member and one of said links to force the friction surfaces of said links together, said resilient member having turned projections for straddling the longitudinal edges of one of said links, one of said projections extending beyond the others to engage one of the edges of the second link when the links are swung to a predetermined position.
- 50 5. In a storm sash holder, an inner link and an outer link having overlapping ends pivoted together, means for pivotally connecting said outer link with a storm sash, said inner link having an apertured end, an attachment bracket mounted on a window frame and having a projecting pivot of substantially the length of the thickness of said inner link and adapted to receive the apertured end of said link and a keeper in the
- form of a lever pivoted to said bracket and having an elongated handle end and a relatively short retaining end, said retaining end being swingable across the end of said pivot and the engaged portion of said link 70 and when in said position permitting free oscillation of said link on said pivot within wide limits.
- In testimony whereof I affix my signature.
